UNITED STATES PATENT OFFICE

166,659

COSMETIC CONTAINER

Rocco A. Colotti, Brooklyn, N. Y., assignor to Victor Industries Corporation, Brooklyn, N. Y., a corporation of New York

Application February 5, 1952, Serial No. 18,391

Term of patent 14 years

(Cl. D86—10)

To all whom it may concern:

Be it known that I, Rocco A. Colotti, a citizen of the United States, residing at Brooklyn, city of New York, in the county of Kings and State of New York, have invented a new, original, and ornamental Design for Cosmetic Container, of which the following is a specification, reference being had to the accompanying drawing, forming part thereof.

Fig. 1 is a top plan view of a cosmetic container, showing my new design.

Fig. 2 is an elevational view thereof.

I claim:

The ornamental design for a cosmetic container, substantially as shown.

ROCCO A. COLOTTI.
